UNITED STATES PATENT OFFICE.

LESTER W. BOND, OF NEW YORK, N. Y., ASSIGNOR TO BERBECKER & ROWLAND MANUFACTURING COMPANY, OF WATERVILLE, CONNECTICUT, A CORPORATION OF CONNECTICUT.

EXTENSION-ROD.

1,115,492.

Specification of Letters Patent.

Patented Nov. 3, 1914.

Application filed February 16, 1914. Serial No. 818,850.

To all whom it may concern:

Be it known that I, LESTER W. BOND, a citizen of the United States, and a resident of New York, borough of Manhattan, in the county of New York and State of New York, have made and invented certain new and useful Improvements in Extension-Rods, of which the following is a specification.

10 My invention relates to an improvement in extension rods for curtains, draperies, etc., and more particularly to the brackets or supporting devices for the ends of what are usually known as and termed goose-neck rods, the object of the invention being 15 to provide brackets which may be easily and readily attached to, and detached from, a window or door frame, or other support; which may be manufactured at a nominal 20 cost; which, while being made preferably from wire, will be sufficiently strong to withstand the strain usually put upon similar devices, and with which the rod may be quickly associated or assembled without 25 danger of becoming accidentally disengaged therefrom.

A further object of my invention is to so 30 construct the bracket that it will be entirely concealed within the rod when in use, thereby imparting to the article a neat and finished appearance, and with these and other ends in view consists in certain novel 35 features of invention and combinations of parts as will be hereinafter fully described and pointed out in the claims.

In the accompanying drawings, Figure 1 is a view of a goose-neck extension rod supported upon brackets constructed in accordance with my invention. Fig. 2 is a 40 side view of one of the brackets, the rod being detached. Fig. 3 is a similar view of the bracket, one end of the rod being shown in section and assembled therewith. Fig. 4 is a detached view in perspective of 45 one of the brackets, and Fig. 5 is a similar view of a modified form thereof.

Referring to the drawings, 6 represents an extension rod, the ends 7 being curved or bent as illustrated, the rod being of that 50 form usually known as telescopic or extension rods, that is, formed of two sections, one telescoping within the other, although it will of course be understood that my invention is not in any wise limited or restricted to any particular form or construc-

tion of rod, the gist of the invention lying more particularly in the bracket for supporting the ends thereof, it being essential, however, that the ends of the rod be made hollow in order to receive and contain the brackets as will be hereinafter understood.

Heretofore it has been the custom to form supporting brackets for the ends of the rod in various ways, and to provide such with screws or holding devices, the major portion of these brackets, in addition to the holding devices, being exposed to view, thus, in a large measure, especially with the cheaper form of rods, detracting from the neat and finished appearance thereof. To overcome this objection, I have constructed and arranged the brackets so that when the parts are assembled, they will be entirely concealed from view, each of these brackets being preferably formed of wire having more or less spring or resiliency, the wire being bent to form an arm or loop 8 of any desired length, but sufficient to sustain the weight of the rod 6 and any strain which might be imposed upon the latter. This 55 loop 8, comprising in its preferred form, two strands of wire 9, 10, has one end thereof bent or curved into the form of an eye 11, through which is passed a screw 12 employed for the purpose of anchoring or securing the end of the bracket to the window or door frame, or other support 13, as clearly illustrated in Figs. 2 and 3 of the drawing, the one arm 9 of the loop therefor being stationary or rigid. The extreme end 90 14 of the arm or strand 10 of the loop is left free and slightly bent away from or separated from the strand 9, as illustrated in Figs. 2, 4 and 5, this extreme end being preferably straight as illustrated in Figs. 2 and 4, or slightly curved outwardly as illustrated at 15, Fig. 5. The eye 11 formed on the end of the strand 9 is of such diameter that it may be contained within the hollow end of the rod 6.

When the parts are assembled, as illustrated in Fig. 1, the loops 8 are entered into the hollow ends of the rod, the latter fitting tightly up against the window or door frame 13 and entirely concealing the brackets from view, the spring arm 10 being slightly bent inwardly, that is, substantially parallel with the strand 8, as illustrated in Figure 13, the tension of said spring arm being sufficient 105 to prevent the rod from becoming accident- 110

tally disengaged therefrom, although permitting the rod to be detached therefrom by a slight pull, when so desired.

By so constructing and assembling the several parts, it will be understood that the bracket is entirely concealed from view, as is also the retaining screw for securing the bracket in place, thereby imparting a particularly neat and pleasing appearance to the article, as a whole. It will also be understood from the foregoing that these brackets are extremely cheap to manufacture, easily and readily secured in place by means of a single holding screw, and may be made as light or heavy as desired, in accordance with the thickness or gage of the wire employed in their construction.

What I claim is:—

1. A curtain rod having hollow ends, of supporting brackets therefor, each of said brackets comprising an arm provided with means for securing the same to a support, said arms and securing means fitting wholly within the hollow ends of said rod and entirely concealed therein.
2. In a device of the character described, the combination with a curtain rod and supporting brackets therefor, each of said brackets comprising a piece of wire bent to form a loop, one end of said wire being secured

to a support, and the opposite end being free to form a spring arm.

3. In a device of the character described, the combination with a curtain rod having hollow ends, of supporting brackets therefor, each of said brackets being formed of a single piece of wire bent to form a supporting loop, one end of said wire being secured to a support, and the opposite end being free to form a spring arm, said loop fitting within the hollow end of said rod. 35

4. In a device of the character described, the combination with a curtain rod having hollow ends, of supporting brackets therefor, each of said brackets being formed from a single piece of wire bent to form a supporting loop, one extreme end of the wire being formed into an eye for the reception of a retaining screw, the opposite end of said wire being free, said loop and eye fitting within the hollow end of said rod and entirely concealed therein. 45

Signed at New York, borough of Manhattan, in the county of New York and State of New York, this 7th day of February, 55 A. D. 1914.

LESTER W. BOND.
